MEANS FOR OPERATING DOORS

Winfred P. Shepherd, Pasadena, Calif.

Application May 5, 1941, Serial No. 391,878

7 Claims. (Cl. 16—1)

The object of this invention is to provide a simple and convenient means of holding the door in a closed position, for easily opening the door and for holding it in an approximately horizontal position when open.

A further object of the invention is to provide an arrangement of operating parts which will eliminate or hold to a minimum, the vibration and consequent rattle that characterizes some such compartment doors now in use.

Following is a specification of the device:

In the accompanying drawing,

Fig. 1 is a front view of the door with its location in an automobile indicated.

Fig. 2 is a sectional view taken through the line 2—2.

Fig. 3 is a diagrammatic sketch indicating the duplicate arrangement of lever systems.

The compartment closure herein referred to, preferably comprises a door 10, mounted preferably on spring hinges 11 which open the door, preferably downwardly when the catch 19, hereinafter described, is released. Rigidly attached to the edge of the door 10, as by spot-welding, at a suitable distance from its hinges 11, is a clip 12, on which is pivoted a lever 13, preferably curved in a quarter circle at the opposite end 14. At the curved end 14 of the lever 13 is pivoted at 15 a second lever 16, the other end of which is pivoted at 17 to the side housing 23 of the compartment. The location of clip 12 and of the pivots 15 and 17 is such that the action lines of levers 13 and 16 are approximately (but not quite) parallel when the door 10 is closed. Thus the moment of force tending to rotate lever 16 is very small and the pull of the spring hinges 11 on the door 10 is mainly resisted by the pivot 17 and the pressure against the catch 19 is relatively small.

In the closed position of the door 10, the pivoted end 15 of the lever 16 extends beyond the curved portion 14 of lever 13, forming a hook or dog 18 which engages catch 19 and holds the door tightly shut. Catch 19 is pivoted preferably on the side housing 23 at 20. A spring 21 holds the catch 19 in its forward or engaged position. A lug 22, preferably stamped in side housing 23, limits the forward movement of the catch 19 when the door is opened.

A small knob or stop 24, preferably stamped in the side housing 23, serves to limit the rotation of lever 16 when the door 10 opens and thus holds it in an approximately horizontal position.

Pivoted to clips 25, rigidly attached as by spot-welding to the under side of the bottom

housing 26 of the compartment, a bar 27, approximately as long as the door is wide, is located so it can be manipulated easily by the fingers. A hooked rod or wire 28 connects the bar 27 with the lower end 29 of the catch 19.

Felt or rubber cushions 30 are provided in the front housing 31 of the compartment, to prevent the door from rattling.

The operation of the device is as follows:

With the door 10 in closed position, a slight pull on the bar 27 pulls forward the lower end 29 of catch 19 and thus releases the catch. The pull of the spring hinges 11 opens the door and levers 13, 16 preferably assume the positions shown in Fig. 2, lever 16 rotating about the pivot 17 until it rests against the stop 24, to hold the door in a horizontal position. The catch 19 is prevented from moving too far under the pull of the spring 21 by the lug 22.

The door is closed by merely pushing against it with the hand till it stops against the cushions 30. In closing the door 10, lever 13 rotates lever 16 till the end 18 engages catch 19, thus locking the door against the pull of the springs in hinges 11. This strain of spring hinges 11 tends to keep the door from rattling and immediately opens the door 10 upon release of the catch 19, as stated above.

In this specification, to simplify the description, the levers 13 and 16, catch 19, spring 21 and correlative parts are spoken of in the singular number, whereas they would be preferably in duplicate, for each edge of the door, as indicated by Fig. 3.

It will be understood that various changes and modifications in the means herein disclosed may be made without departing from the spirit and scope of the invention as defined in the appended claims.

I claim as my invention:

1. In combination with a compartment door hinged at the bottom, two levers pivoted together, the first of said levers being pivoted to said door and the second of said levers being pivoted to a stationary member in such relative positions that the levers will be approximately normal to each other when the door is open and rotated to a position approximately parallel when the door is closed, releasable means for holding the levers in said approximately parallel position, an elongated rigid member movably mounted in a horizontal position below said compartment adapted to release said holding means, and spring means operable upon release of said holding means to open said door.

2. In combination with a compartment door hinged at the lower edge, two levers, one approximately twice as long as the other, pivoted together, the longer of said levers being pivoted to said door and the shorter of said levers being pivoted to a stationary member, in such relative positions that the two levers will be approximately normal to each other when the door is open and rotated to a position approximately parallel when the door is closed, a spring catch pivoted on a stationary member adapted to engage the end of the shorter lever when said door is closed, and means for releasing said catch.

3. In combination with a compartment door hinged at the bottom, two levers of unequal length pivoted together, the longer of said levers being pivoted to said door and the shorter of said levers being pivoted to a stationary member in such relative positions that the two levers will be approximately normal to each other when the door is open and rotated to a position approximately parallel when the door is closed, a spring catch pivoted on a stationary member adapted to engage the shorter of said levers to hold the door in closed position, and an elongated, rigid member movably mounted parallel to the hinged edge of said door, adapted to release said catch.

4. In combination with a compartment door hinged at the bottom, two levers of unequal length pivoted together, the longer of said levers being curved in approximately a quarter circle at one end and at the other end pivoted to said door and the shorter of said levers being pivoted to a stationary member, means for holding said levers from rotating about their respective pivots when the door is in closed position, means for releasing said holding means, and means for swinging the door to open position when said holding means is released.

5. In combination with a compartment door hinged at the lower edge, two levers pivoted together, one of said levers being pivoted to said door and the other lever being pivoted to a stationary member, a catch pivoted on a stationary member, adapted to engage one of said levers to hold them from rotating about their respective pivots when the door is in closed position, a bar approximately as long as the door is wide, movably mounted parallel to the hinged edge of said door adapted to release said catch, and means for swinging the door to open position when the catch is released.

6. In combination with a compartment door, hinged horizontally and having a latch engaging means, a spring biased latch pivotally mounted on a stationary member for engagement with said latch engaging means to hold said door in a closed position, a rigid member movably mounted below the hinged edge of said door, and an elongated connecting member connecting the latch and rigid member to release said latch upon movement of the rigid member.

7. In combination with a compartment door hinged at the lower edge and having a latch engaging means adjacent each side edge thereof, a pair of spring biased latches pivotally mounted on a stationary member for engagement with said latch engaging means to hold the door in closed position, a rigid member, approximately as long as the door is wide, movably mounted parallel to the hinged edge of said door, and a pair of connecting members pivoted to the latch and the respective ends of said rigid member to release said latches upon movement of the rigid member.

WINFRED P. SHEPHERD.
